UNITED STATES PATENT OFFICE.

JAMES W. CAMPBELL, OF GERMANTOWN, ASSIGNOR TO THE FERGUSON BROTHERS, OF NEW YORK, N. Y.

DESIGN FOR A HOOK-RACK.

SPECIFICATION forming part of Design No. 19,322, dated October 1, 1889.

Application filed August 20, 1889. Serial No. 321,409. Term of patent 3½ years.

To all whom it may concern:

Be it known that I, JAMES W. CAMPBELL, of Germantown, Columbia county, and State of New York, have invented and produced a certain new and useful Design for a Hook-Rack for Garments, &c., of which the following is a specification.

The accompanying drawing is a perspective view of a hook-rack embodying my improvement.

The design consists of an upright disk A, a horizontal semicircular bracket B, which is arranged to project from said disk in a posi-

tion directly across the same, and hooks C, of substantially semicircular form, dependent from the said bracket and projecting horizontally beyond it.

What I claim as my design, and desire to secure by Letters Patent, is—

A design for a hook-rack, substantially as herein shown and set forth.

JAMES W. CAMPBELL.
